UNITED STATES PATENT OFFICE

2,474,938

CAVITY RESONATOR ELECTRON
DISCHARGE DEVICE

Elmer J. Gorn, Newton, Mass., assignor to Raytheon Manufacturing Company, Newton, Mass., a corporation of Delaware

Application September 12, 1944, Serial No. 553,763

7 Claims. (Cl. 315—40)

1

This invention relates to electron discharge devices of the type in which it is desired to impart high speeds to electrically charged particles for various purposes, and particularly to devices in which it is desired to impart high speeds to electrons and to derive high voltages therefrom.

For many purposes it is desirable to convert relatively low voltage alternating current or direct current into a high voltage direct current. Such conversion has heretofore involved the use of expensive equipment.

It is among the objects of the present invention to provide a novel means and method for converting relatively low voltage currents into high voltage currents without resorting to expensive and cumbersome apparatus.

The above and other objects of the invention will be made fully apparent to those skilled in the art from a consideration of the following detailed description taken in conjunction with the accompanying drawing in which:

Fig. 1 shows a section taken on the line X—X of Fig. 2 through a high voltage generator constructed in accordance with the invention;

Fig. 2 shows a section taken on the line Y—Y of Fig. 1;

Fig. 3 shows the device in side elevation and on a scale substantially reduced from that of Figs. 1 and 2; and

Fig. 4 shows a fragmentary section taken on the line Z—Z of Fig. 1.

Referring to the drawing, reference numeral 1 indicates an envelope consisting of a block of highly conductive material, such as copper, and having a pair of substantially cylindrical chambers 2 and 3 constituting a generating and a receiving chamber, respectively, and each providing the anode structure of a magnetron. The cylindrical chambers 2 and 3 have internal shouldered portions 4 and 5, respectively, intermediate the length thereof. Central bores 6 and 7 extend axially through the shouldered portions 4 and 5. The shouldered portions 4 and 5 each has an even number of bores 8 and 9, respectively, extending through the peripheral portions thereof and disposed symmetrically around the bores 6 and 7 and connected therewith by radial slots 10 and 11. The structure thus provides a plurality of radially extending arms 12 and 13 in the cylindrical chambers 2 and 3, respectively. Cathode structures 14 and 15 are centrally mounted in the bores 6 and 7. The cathode structures 14 and 15 comprise hollow cylindrical members 16 and 17 of conductive material having activated outer surfaces and internal heat-

2

ing elements 18 and 19. The hollow cylindrical members 16 and 17 extend parallel with the inner faces of the anode arms 12 and 13 and are spaced therefrom by annular spaces 20 and 21. The cathode structure 14 is supported in spaced position relative to the anode arms by conducting rods 22 and 23 extending axially from each end of the cathode structure into the end portions of the cylindrical chamber 2. Both of the conducting rods 22 and 23 are electrically connected to the heater 18 and one of them is also connected to the hollow cylindrical member 16 to supply a negative potential thereto while the other is insulated therefrom. The conducting rods 22 and 23 are secured, as for example by welding, to the inner ends of lead-in conductors 24 and 25. The lead-in conductor 24 extends through a conductive pipe 26 hermetically sealed in the wall of the envelope 1 and has its outer end sealed through a glass seal 27 supported at the outer end of the conductive pipe 26. The other lead-in conductor 25 extends through a similar conductive pipe, not seen in the drawing, at the lower end of the cylindrical chamber 2. The cathode structure 15 is likewise supported by conducting rods 30 and 31 projecting axially therefrom which are connected to the cathode structure in the same manner as previously described in connection with the conducting rods 22 and 23, which conducting rods are likewise connected to and supported by lead-in conductors 32 and 33. The lead-in conductor 32 extends through a conductive pipe 26 having a glass seal 27 and the lead-in conductor 33 extends through a similar mounting, not seen in the drawing, at the lower end of the cylindrical chamber 3.

The cylindrical chambers 2 and 3 are spaced in the block 1 so as to provide a partition 34 therebetween. The partition 34 has an iris opening 35 therethrough connecting one of the bores 8 of the chamber 2 with one of the bores 9 of the chamber 3. End caps 36 and 37, hermetically sealed to the block 1 in closing relation to the ends of the cylindrical chambers 2 and 3, complete the enclosure of the evacuated space of the device. Pole pieces 38 and 39, adjacent the portion of the end caps 36 and 37 closing the chamber 2, provide a magnetic field extending longitudinally of this chamber, and pole pieces 40 and 41, similarly positioned relative to the chamber 3, provide a magnetic field extending longitudinally of the chamber 3. The pole pieces 38 and 39 may be the opposite poles of a permanent magnet formed of a material having a

high coercive force, such as suitable alloys known in the art. Preferably, however, in order to vary the magnetic field I provide a core 42 of highly permeable magnetic material connecting the pole pieces 38 and 39, which core has a winding 43 energized from a suitable source of direct current 44 controlled by a rheostat 45. Similarly, the pole pieces 40 and 41 are connected by the core 46 having a winding 47 energized from a source 48 controlled by a rheostat 49.

The filaments 18 and 19 are adapted to be supplied with heating current by means of a circuit including a transformer 50 having a primary winding 51 and a secondary winding 52. The opposite ends of the primary winding 51 are connected to a suitable source of alternating current, not shown. One end of the secondary winding 52 is connected by a wire 55 to the lead-in conductor 24 and by a wire 56 to the lead-in conductor 32. The opposite end of the secondary winding 52 is connected by a wire 57 to the lead-in conductor 25 and is also connected by a wire 58 to the lead-in conductor 33.

It will be seen that by this circuit an alternating heating current is continuously supplied through the heating elements 18 and 19. A biasing potential is applied between the anode arms 12-13 and the cathode sleeves 16-17 from a transformer 53, the primary winding of which is connected to a suitable source of alternating current, not shown, and the secondary winding of which is connected at one end by way of a switch 54 to the envelope 1. The opposite end of the secondary winding of the transformer 53 is connected to the lead lines 55 and 56 of cathode heater circuit. It will be seen that, during that half wave of the alternating current from transformer 53 when a positive potential is applied to the envelope 1 and hence to the anode arms 12 and 13, a negative potential will be applied to the hollow cylindrical members 16 and 17 which are directly connected to the uppermost of the lead-in conductors 24 and 32 and insulated from the lowermost of the lead-in conductors 24 and 32. Thus a potential difference is applied between each of the cathode sleeves 16, 17 and the adjacent end faces of the respective anode arms 12 and 13 during this half wave of the alternating current. During the opposite half wave, the potential between the arms and the sleeves is reversed and the device does not utilize this half wave.

Within the central bore 1 of the chamber 3 is a target 59. The target 59 is formed of a strip of conductive material extending longitudinally through substantially the entire length of said bore. The target is positioned to project from the inner end of one of the slots 11 into the annular space 21 between the cathode structure 15 and the inner end faces of the anode arms 13. The target 59 is supported in the desired position by a lead-in conductor 60, the inner end of which is welded or otherwise rigidly secured to the target at a point intermediate the ends thereof. The lead-in conductor 60 extends through one of the slots 11 and its corresponding bore 9 and outwardly through a conductive pipe 61 hermetically sealed through the wall of the envelope 1. The outer end of the lead-in conductor 60 is sealed through a glass seal 62 hermetically closing the outer end of the conductive pipe 61. The conductor 60 may be connected to any suitable utilization device. In the instance shown, this utilization device is illustrated diagrammatically as an electric

precipitator comprising an extension of the conductor 60 passing centrally through a conductive sleeve 63, which sleeve is grounded by a conductor 64.

5 In the operation of the device described in the foregoing, when the device is energized, the left-hand side thereof comprising the chamber 2 and its associated parts functions as a generator of ultra-high frequency oscillations in the manner of a magnetron.

It will be understood that in the operation of such magnetrons, capacitances exist between the cathode member 16 and the adjacent end face of each of the anode arms 12. Capacitances also 15 exist between the adjacent side faces of the anode arms 12 across the slots 10. The inner walls of the bores 8 constitute inductances. The anode is so designed and spaced relative to the cathode that the capacitances and the inductances described constitute circuits which are 20 tuned. These circuits are resonant at a predetermined frequency depending upon the geometry of the tube, each bore 8 and its adjacent arms forming a circuit tuned to the frequency at 25 which each of the other bores 8 and its adjacent arms oscillate. In other words each bore 8 and its associated slot constitute a resonant cavity. In such magnetrons the electrons emitted from the 30 active surface of the cathode 16 move in orbital paths around the cathode in the annular space 20 and in so moving give up energy to the resonant circuits described during those periods when the polarity of the energizing circuits is in the proper direction, thereby maintaining or increasing the intensity of the oscillations in said resonant cavities.

Oscillations generated in the resonant cavities of the chamber 2 are fed into similar resonant cavities provided by the bores 9 of the chamber 40 3 by way of the iris opening 35. The cavities provided by the bores 9 are designed to oscillate at the same frequency as the cavities provided by the bores 8, and accordingly the oscillations fed into the resonant cavities of the chamber 45 3 from the resonant cavities of chamber 2 induce oscillations in the resonant cavities of the chamber 3. When the cavities are so oscillated, electrons emitted from the cathode sleeve 17 derive energy from the oscillations of the resonant cavities of the chamber 3 receiving an angular acceleration. The strength of the magnetic field through the chamber 3 is adjusted by the rheostat 49 so that those electrons whose angular motion coincides with the phase of the oscillations 50 are driven into the target 59, imparting a high negative voltage to it. The target being insulated from the other elements of the device, this voltage tends to build up to a value corresponding to that of the highest speed electrons. 55 This voltage may be utilized for any suitable purpose such as the electrostatic precipitator shown or for X-ray tubes or other high voltage direct current devices.

While the device has been shown as comprising 60 a single envelope having a pair of chambers interconnected, it will be apparent that these chambers may be provided in separate envelopes connected together by any suitable transmission line for transmitting the oscillations generating 65 in one of the envelopes to the other. Such separation of the two sections of the device is advantageous where it is desired to apply a different biasing potential to one of the sections than to the other.

70 While there has been herein described a pre-

ferred embodiment of the invention, other embodiments within the scope of the appended claims will be apparent to those skilled in the art from a consideration of the embodiment shown and the teachings hereof. For example, it will be apparent that the device may be energized by direct current rather than alternating current as shown, and that when so energized the device will generate a high voltage, continuous direct current, rather than a pulsating direct current. Also it will be apparent that certain parts may be duplicated. In some instances a plurality of targets 59 spaced about the annular chamber 21 may be utilized instead of the single target shown.

What is claimed is:

1. A device for imparting high velocities to electrically charged particles comprising an evacuated envelope containing a plurality of cavity resonators and a source of charged particles, means adjacent said envelope for creating a magnetic field directed transversely to the paths of said charged particles whereby the charged particles are given an orbital motion, means coupled to said cavity resonators to supply oscillations to said cavity resonators at the resonant frequency thereof, said cavity resonators being symmetrically spaced along the orbital paths of said electrons to produce a varying electrostatic field for accelerating said charged particles, and a target separate from said cavity resonators positioned in the path of said charged particles to intercept the same and provide a voltage corresponding to the velocity thereof.

2. A device for imparting high velocities to electrically charged particles comprising an evacuated envelope containing a plurality of cavity resonators and a source of electrons, means adjacent said envelope for creating a magnetic field directed transversely to the paths of said electrons whereby the electrons are given an orbital motion, means coupled to said cavity resonators to supply oscillations to said cavity resonators at the resonant frequency thereof, said cavity resonators being symmetrically spaced along the orbital paths of said electrons to produce a varying electrostatic field for accelerating said electrons, and a target separate from said cavity resonators positioned in the path of said electrons to intercept the same and provide a voltage corresponding to the velocity thereof.

3. A device for generating a high voltage comprising an envelope having an evacuated space, a source of electrons in said space, means adjacent said envelope for creating a magnetic field through which said electrons pass whereby said electrons move through said space in orbital paths, means in said space for subjecting said electrons to a varying electrostatic field to give said electrons a plurality of accelerations thereby imparting a high velocity thereto, and a target positioned in the path of said electrons, said target being electrically insulated from the other parts of said device whereby electrons are accumulated upon said target and impart a negative voltage thereto.

4. A device for imparting high velocities to electrons comprising a sealed envelope containing a pair of chambers providing a generating chamber and a receiving chamber, electrode elements providing cavity resonators within the evacuated space of each of said chambers, said elements including a cathode and an anode in each of said chambers, means adjacent said generating chamber for establishing a magnetic field

therethrough in a direction transverse to the path between the cathode and anode therein whereby electrons emitted by said last-named cathode are caused to follow orbital paths and generate ultra high frequency oscillations in said generating chamber, and means intermediate said generating and receiving chambers to transmit said ultra high frequency oscillations from said generating chamber to said receiving chamber to induce oscillations in the cavity resonators of said receiving chamber.

5. A device for imparting high velocities to electrons comprising a sealed envelope containing a pair of chambers providing a generating chamber and a receiving chamber, electrode elements providing cavity resonators within the evacuated space of each of said chambers, said elements including a cathode and an anode in each of said chambers, means adjacent said generating chamber for establishing a magnetic field therethrough in a direction transverse to the path between the cathode and anode therein whereby electrons emitted by said last-named cathode are caused to follow orbital paths and generate ultra high frequency oscillations in said generating chamber, a partition between said chambers, said partition having an opening therethrough connecting a cavity resonator of said generating chamber to a cavity resonator of said receiving chamber to transmit said ultra high frequency oscillations from said generating chamber to said receiving chamber to induce oscillations in the cavity resonators of said receiving chamber.

6. A device for imparting high velocities to electrons comprising a sealed envelope containing a pair of chambers providing a generating chamber and a receiving chamber, electrode elements providing cavity resonators within the evacuated space of each of said chambers, said elements including a cathode and an anode in each of said chambers, means adjacent said generating chamber for establishing a magnetic field therethrough in a direction transverse to the path between the cathode and anode therein whereby electrons emitted by said last-named cathode are caused to follow orbital paths and generate ultra high frequency oscillations in said generating chamber, means intermediate said generating and receiving chambers to transmit said ultra high frequency oscillations from said generating chamber to said receiving chamber to induce oscillations in the cavity resonators of said receiving chamber whereby the electrons emitted from the cathode of said receiving chamber are accelerated in an oscillating electrostatic field, and a target positioned in the path of said accelerated electrons.

7. A device for imparting high velocities to electrons, a sealed envelope containing a pair of chambers providing a generating chamber and a receiving chamber, electrode elements providing cavity resonators within the evacuated space of each of said chambers, said elements including a cathode and an anode in each of said chambers, means adjacent said envelope providing a magnetic field through said generating chamber transverse to the path of electrons emitted from the cathode thereof and coaxing with the electrostatic field of said resonant circuits to generate ultra high frequency oscillations in said generating chamber, means intermediate said generating and receiving chambers to transmit said ultra high frequency oscillations from said generating chamber to said receiving chamber to induce oscillations in the cavity resonators of said receiving

ing chamber, means adjacent said envelope providing a magnetic field through said receiving chamber whereby electrons emitted from the cathode of said receiving chamber move in orbital paths and are accelerated in an oscillating electrostatic field, and a target positioned in the path of said accelerating electrons.
